UNITED STATES PATENT OFFICE.

ISABEL O. KILEY, OF JACKSONVILLE, FLORIDA.

TRAP.

Application filed March 20, 1923. Serial No. 626,374.

To all whom it may concern:

Be it known that I, ISABEL O. KILEY, a citizen of the United States, residing at Jacksonville, in the county of Duval and State of Florida, have invented certain new and useful Improvements in a Trap; and I do hereby declare the following to be a full, clear, and exact description of the invention, such as will enable others skilled in the art to which it appertains to make and use the same.

This invention relates to a trap which while capable of broader use is primarily designated to catch roaches.

It is aimed to provide a construction in which an attaching element is provided to afford an entrance to the trap and which has its inner end at a distance above the base of the trap so that the captive will be forced to fall or jump in order to enter the trap and which aids in preventing its escape.

Another object is to provide a construction wherein a catching element is provided having a lateral flange adapted to be removably carried by a cover of the trap and held secured to the cover by a removable clamp plate, and with the cover and plate constituting reinforcing means to more rigidly mount and support the catching member.

Additional objects and advantages will become apparent from a consideration of the description following taken in connection with accompanying drawings illustrating one practical embodiment.

In said drawings:

Figure 1 is a perspective view of the trap; Figure 2 is a central longitudinal sectional view of the trap; and

Figure 3 is a detail perspective view illustrating the catching member, the trap closure and the clamping plate in disassociated relation.

Like reference characters designate like or similar parts in the different views.

In reducing the invention to practice, a receptacle is provided as at 10 which is of any suitable shape or size or material. It is preferably made of metal and closed at four sides and one end as shown, thus leaving the other end open or exposed.

Cooperating with the open end of the receptacle 10 is a catching element 11. This element may consist of a conical tube made of any suitable material, preferably metallic gauze, and having integral therewith or otherwise provided, an attaching flange 12,

disposed at its larger or entrance end. Its escape end is smaller and designated 13. Said end 13, it will be noted is disposed at a distance above the base wall of receptacle 10.

A closure for the open end of receptacle 10 is provided as at 13', and may be a metallic plate as shown having a continuous marginal flange at 14 for removable frictional telescopic engagement with the open end of receptacle 10. The closure 13' is adapted to removably mount the catching member 11 and to this end has a central opening 15 therethrough to register with the bore of the cube 11. The flange 12 is removably disposed against the inner surface of the closure 13' and conforms substantially in shape to that of the closure and has its marginal edge surrounded or bordered by the flange 14.

A clamping plate 16, for instance of metal, is adapted to secure the catching element 11 to the closure 13' removably. This plate is substantially the same shape as the flange 12, having an opening at 17 through which the tube 11 extends and being of such size that its marginal edge will frictionally engage the marginal edge of flange 14 at the inner surface thereof.

It will thus be seen that the attaching element may be rigidly and removably secured to the closure 13'. Further attention is called to the fact that as the closure 13' is removably telescoped with the receptacle 10, the adjacent edge of said receptacle abuts the plate 16, thus serving to more rigidly and effectually secure attaching member 11 to the plate.

In actual use, bait may be disposed within the receptacle, as suggested at 18 and may be for instance a small piece of bread and a small piece of onion. I have found that such material forms a good bait for roaches and that roaches will enter the tube 11 and fall or jump from the end 13 into the interior of the receptacle 10 whereby they are captured. As the end 13 is spaced from the walls of the receptacle, particularly the bottom wall, captives cannot enter it in order to escape.

Due to the fact that every part utilized in the trap may be separably or detachably connected from the other parts, the trap may be readily cleaned as in boiling water, when desired.

As merely one practical embodiment has

been illustrated and described, it is to be understood that changes in the details may be resorted to provided they fall within the spirit and scope of the invention.

5 I claim as my invention:

A trap consisting of a receptacle, a closure therefor having a marginal attaching flange insertable into the receptacle, a catching means consisting of a tube and a flange 10 extending laterally from said tube, said flange being removably disposed against said closure and bordered by said first mentioned flange, said closure having an opening communicating with the tube, a 15 clamp plate having an opening through

which said tube extends engaging the second mentioned flange on the opposite side to the closure and bordered by and in frictional engagement with the first mentioned flange whereby when the closure is applied to the 20 receptacle, the first flange will be disposed in intimate contact with the adjacent portion of the receptacle.

In testimony whereof I affix my signature in presence of two witnesses.

ISABEL O. KILEY.
